UNITED STATES PATENT OFFICE

CLAUDE W. SAMS, OF HUNTINGTON, WEST VIRGINIA

DESK CABINET

Application filed October 6, 1931. Serial No. 567,254.

This invention has for its object the provision of means whereby a blotter pad will be held against slipping around upon a desk and means will be provided for storing papers which are frequently needed by the occupant of the desk whereby the papers will be accessible whenever needed. The invention is illustrated in the accompanying drawing and will be hereinafter fully set forth and defined.

In the drawing,

Figure 1 is a perspective view of a desk cabinet and blotter pad embodying the invention,

15 Fig. 2 is a section on the line 2—2 of Fig. 1.
Fig. 3 is a section on the line 3—3 of Fig. 1.

In carrying out the present invention, there is provided a plate 1 which may be of cardboard, light metal or other material 20 which will retain its shape and will rest flat upon a desk top without marring the surface. At two corners of this base or plate are provided triangular pockets 2, of well known form, which receive and retain the front corners of a sheet of blotting paper, indicated at 3. The corners of the base 1, provided with the pockets 2, will be disposed at or adjacent the front edge of the desk top and the opposite end of the plate will be disposed at or adjacent the back edge of the desk. Upon the rear portion of the base 1 are erected cabinets 4 and 5 which may be of any desired dimensions and will serve to hold the base upon the desk and prevent it 30 from sliding or slipping around on the desk top to the annoyance of the user. The cabinets have their back walls located at the back edge of the plate 1 and they extend the full width of the plate, as indicated at 6. The

40 cabinet 4 consists of vertical side walls 7 joined by a top 8 and having horizontal partitions 9 extended between them at an intermediate point in their height, said partitions 9 being spaced vertically to receive a drawer 10, as clearly shown. Between the upper partition 9 and the top of the cabinet, a vertical partition 11 is provided midway the side walls 7 and between the lower partition 9 and the bottom of the cabinet a similar partition 12 is provided thereby subdividing the

cabinet into pigeon holes which may receive various articles constantly employed by the occupant of the desk. The cabinet may be provided with a bottom plate 13 or the base 1 of the pad may be utilized as the bottom of 55 the cabinet, but in either event, the side members and the vertical partitions of the cabinet will be provided with shallow notches 14 at their lower forward corners to accommodate the rear edge of the blotter sheet 3 so 60 that said sheet will be firmly retained in place and kept in a smooth condition.

The cabinet 5 is similar in construction to the described cabinet 4, having two side walls and a top 15 connecting said side walls and 65 having horizontal partitions 16 whereby the cabinet is subdivided into three compartments which receive drawers 17. In Fig. 3 the lowest drawer 17 is shown as resting upon cleats 18 and the forward cleat is notched, as 70 at 19, to accommodate the rear edge of the blotting sheet.

Extending between and secured to the inner side wall of the two cabinets are inclined shelves 20 and 21 which coact with the sides 75 of the cabinets and the back plate 6 to define pockets in which papers or other articles may be placed, the area of the base 1, in front of the lower shelf 20, being available for placing an ink stand and similar articles. It 80 will be noted, upon reference to Fig. 2, that the shelves 20 and 21 are located some distance in advance of the back plate and the lower edge of the upper shelf 21 is connected 85 to the back plate by a bottom bar or rail 22 so that a positive support for the papers will be provided.

From the foregoing description, taken in connection with the accompanying drawing, it will be seen that I have provided a compact, simple and inexpensive article of desk furniture whereby the advantages of the usual blotting pad will be retained and the pad will be kept in its proper position upon the desk at all times while a convenient means for holding letterheads, envelopes and similar articles which are constantly needed by the occupant of the desk will be provided. The cabinets and the shelves, furthermore, 95 serve as guards to prevent the ink stand being 100

upset by accidental blows while the shelves at the rear of the ink stand will be accessible at all times and are so disposed that, in order to place paper within the pocket defined by 5 either shelf or to withdraw paper, the occupant of the desk will be obliged to reach over the ink stand in such a manner that he will not be apt to upset it.

Having thus described the invention, I 10 claim,

- Desk furniture comprising a base plate to rest flat upon a desk, a back wall rising from said base plate, a pair of vertical walls rising from the base plate at and adjacent one 15 end of the back wall and extending over the base plate from the back wall, a top and vertically spaced horizontal partitions connecting said vertical walls, cleats on the base plate between the lower edges of said vertical walls 20 at the back wall and at the front edges of the vertical walls, the front cleat having its front edge rabbetted to provide a sheet-receiving recess in its front edge, vertical walls rising from the base plate at and adjacent the opposite end of the back wall and having sheet-receiving recesses at their lower front corners, 25 vertically spaced horizontal partitions and a top connecting said vertical walls, a vertical partition rising from the upper of the last-mentioned horizontal partitions, a vertical partition depending from the lower of said horizontal partitions, inclined shelves extending between the inner vertical walls, and 30 horizontal plates extending between the lower edges of said shelves and the back wall.

In testimony whereof I affix my signature.

CLAUDE W. SAMS. [L. S.]
